UNITED STATES PATENT OFFICE.

FREDERICK A. GIENCKE, OF BROOKFIELD, WISCONSIN.

DESIGN FOR A WIRE-FENCE TOOL.

SPECIFICATION forming part of Design No. 33,469, dated October 30, 1900.

Application filed October 3, 1900. Serial No. 31,932. Term of patent 7 years.

To all whom it may concern:

Be it known that I, FREDERICK A. GIENCKE, a citizen of the United States, residing at Brookfield, in the county of Waukesha and State of Wisconsin, have invented and produced a new and original Design for Wire-Fence Tools, of which the following is a specification, reference being had to the accompanying drawings, forming part thereof.

10 Figure 1 is a perspective view of my invention. Fig. 2 is an end view of the same.

As shown in the drawings, the leading or material features of my design consist in a bar A, provided with right-angled projections B C and a backwardly-extending portion D at one end, said portion being for a part of its

length parallel with the bar A. The portion C is in the form of a tusk, its upper end being curved laterally toward the opposite side of the bar A from that occupied by the part D. 20

Having thus described my invention, what I claim as new, and desire to secure by Letters Patent, is—

25 The design for a wire-fence tool, as herein shown and described.

In testimony whereof I have subscribed my name to this specification in the presence of two subscribing witnesses.

FREDERICK A. GIENCKE.

Witnesses:

LEVERETT C. WHEELER,
JAS. B. ERWIN.
